United States Patent Office

Des. 191,560
Patented Oct. 10, 1961

191,560

RANGE OR SIMILAR ARTICLE

Pierre L. Chabre, Los Angeles, and Clifford D. Mohr,
Downey, Calif., assignors to Utility Appliance Corp.,
Los Angeles, Calif., a corporation of California

Filed Mar. 3, 1961, Ser. No. 64,134

Term of patent 14 years

(Cl. D81—4)

FIG. 1 is a perspective view of a range showing our new design;

FIG. 2 is a front elevation view; and

FIG. 3 is a side view thereof.

The dominant features of our design reside in the portions shown in full lines.

We claim:

The ornamental design for a range or similar article, substantially as shown and described.
